UNITED STATES PATENT OFFICE.

THOMAS GERRARD, OF CORTLAND, NEW YORK, ASSIGNOR OF ONE-HALF TO DANIEL KERNAN, OF CORTLAND, NEW YORK.

OIL-BURNING FURNACE.

1,394,164.

Specification of Letters Patent.

Patented Oct. 18, 1921.

Application filed June 9, 1919. Serial No. 302,713.

To all whom it may concern:

Be it known that I, THOMAS GERRARD, a citizen of the United States, residing at Cortland, county of Cortland, and State of New York, have invented certain new and useful Improvements in Oil-Burning Furnaces, of which the following is a specification.

Reference may be had to the accompanying drawings, and the reference characters marked thereon, which form a part of this specification. Similar characters refer to similar parts in the several figures therein.

This invention relates to a furnace apparatus for burning crude or more less refined oil.

The principal object of the invention is to secure more perfect combustion and greater heating efficiency from the oil.

Other objects will appear in connection with the following description.

Figure 1 of the drawings is a central vertical longitudinal section of my improved oil-burning apparatus applied to an opening in the front wall of an ordinary hot-air heating furnace, the plane of the section being indicated by broken line 1—1 in Fig. 2.

Fig. 2 is a horizontal section of the same taken on the broken line 2—2 in Fig. 1.

Fig. 3 is a cross section of the same taken on the broken line 3—3 in Fig. 1.

Referring to the drawings wherein the invention is shown in preferred form, 1 represents an inclosure provided with an air-inlet, 2, and with a gas-outlet, 3.

This inclosure may be mounted removably or permanently in connection with any heating apparatus into which the gases of combustion are to be directed.

I have shown the inclosure mounted upon a wall, 4, which may be the front wall or front door of an ordinary hot-air heater. The inclosure is thus mounted in such a manner that the gases of combustion will pass into the ordinary fuel-chamber of the heater.

The manner in which the inclosure will be combined with the apparatus in connection with which the heated gases are to be employed will vary in accordance with the nature of the particular apparatus in different cases.

In the construction shown in the drawings, the gas-outlet, 3, is at a lower level than the air-inlet, 2.

Within the inclosure are mounted a top

hearth, 5, a bottom hearth, 6, and an intermediate hearth, 7, all below the level of the air-inlet, 2, and in the general direction of the draft in passing from the air-inlet, 2, to the gas-outlet, 3.

The top hearth, 5, is thus mounted between the levels of said air-inlet and said gas-outlet. Each of the hearths, 6 and 7, has an oil-compartment, 8, and a water-compartment, 9. I have shown the top hearth, 5, as having only an oil-compartment.

The oil-compartments of the several hearths are adapted to receive and support pieces of oil-absorbing refractory material, 25, such as blocks or bodies of asbestos, magnesia or the like. I have found that broken pieces of magnesia clay are satisfactory for this purpose.

Oil is supplied to the top hearth through a pipe, 10, which enters through the side wall of the inclosure, 1, and an excess of oil is delivered from the hearth, 5, by means of an overflow pipe, 11, to the oil-compartment in the next lower hearth, 7.

In a like manner an excess of oil is delivered from the hearth, 7, by an overflow pipe, 12, to the oil-compartment of the bottom hearth, 6. Excess of oil from the bottom hearth, 6, is delivered by an overflow pipe, 13, to a well or sink, 14, in the bottom of the inclosure, whence it is carried by a pipe, 15, to a point outside of the inclosure.

Water is supplied to the water-compartment of the hearth, 7, by means of a pipe, 16, and excess of water is delivered from the hearth, 7, to the water-compartment of the hearth, 6, by means of an overflow pipe, 17.

Excess of water is delivered from water-compartment of hearth, 6, by an overflow pipe, 18, to a well or sink, 19, in the bottom of the inclosure, whence it is carried by a pipe, 20, to a point outside the inclosure.

The lower hearths, 7, and 6, extend successively greater distances toward the front of the inclosure, 1, away from the gas-outlet, 3.

The hearths are slidably mounted upon racks, 21, and can be slid into and out of position within the inclosure through an opening closed by a door, 1^a, which forms part of the front wall of the inclosure.

A flue-space, 22, is formed outside of the front wall of the inclosure-proper, access to which flue can be had through an opening closed by a door, 23, corresponding sub-

stantially with the opening closed by the door, 1^a, thus permitting access to the interior of the inclosure and to the several hearths.

5 The door, 23, is provided with a draft-opening which can be wholly or partly closed by a damper-door, 24, whereby the draft can be regulated.

An important feature of the invention is 10 the admission of the draft to the inclosure at a point above the respective hearths, whereby oil burning on the hearths is exposed to a downward draft of air as the air passes from the inlet, 2, to the gas-outlet, 3.

15 The operation of the apparatus is as follows:

The hearths having been provided with the absorbent refractory material, 25, a supply of oil is admitted through pipe, 10, upon 20 the refractory material in hearth, 5. The oil on hearth, 5, is then ignited, the doors, 1^a and 23, are closed and the damper, 24, is opened. A draft of air is thus caused to pass through the air-inlet, 2, downwardly to 25 the hearth, 5.

As the combustion of the oil proceeds, a high degree of heat is produced, causing a draft of considerable force to pass from the air-inlet 2, through the inclosure and the 30 gas-outlet, 3, and thence to a stack or chimney (not shown) by flues or other means with which the particular furnace apparatus, 4, is provided.

The supply of oil is continued through the 35 pipe, 10, to the hearth, 5, until it overflows through the pipe, 11, to the oil-compartment of the hearth, 7, and if the maximum efficiency of the apparatus is desired, the flow of oil from pipe, 10, is so regulated that the 40 overflow from hearth, 5, supplies an excess of oil to hearth, 7, the overflow from which is supplied by pipe, 12, to the bottom hearth, 6.

By controlling the flow of oil to the pipe, 45 10, by means of a valve, 26, combustion can be maintained on the hearth, 5, alone, or on the hearths, 5 and 7, alone or on all three hearths.

When very high temperatures are main-

tained it is desirable to bring the highly 50 heated gases into contact with a supply of water, and this I accomplish by delivering through pipe, 16, a supply of water to the water-compartment of hearth, 7, the overflow from which passes to the water-compartment of the hearth, 6.

By regulating the supply of water through the pipe, 16, by means of a valve, 27, I can maintain a supply of water in the water-compartment of hearth, 7, alone, or in the 60 water - compartments of both hearths, 7 and 6.

The draft can be regulated by opening the damper-door, 24, more or less or by any ordinary form of damper.

What I claim as new and desire to secure by Letters Patent is—

1. In an oil-burning apparatus and in combination, an inclosure provided with an air-inlet, and with a gas-outlet; a plurality 70 of oil-burning hearths mounted one above another within the inclosure all below the level of said air-inlet; a lower hearth having separate compartments for oil and for water; means for supplying oil directly to 75 only the top hearth; overflow means for delivering an excess of oil from the top hearth to the oil-compartment of said lower hearth; means for supplying water to the water-compartment of said lower hearth; and overflow 80 means for separately conveying an excess of oil from said oil-compartment and an excess of water from said water-compartment to points outside the inclosure.

2. In an oil-burning apparatus and in combination, an inclosure provided with an air-inlet, and with a gas-outlet at a lower level than said air-inlet; a plurality of oil-burning hearths mounted one above another within said inclosure all below the level of 90 said air-inlet with a lower hearth extending a greater distance than the top hearth away from said gas-outlet; and means for supplying oil to said hearths.

In testimony whereof I have hereunto set 95 my hand this 3rd day of June, 1919.

THOMAS GERRARD.
